Primary Examiner — Lauren R Calve(74) *Attorney, Agent, or Firm* — Morrison & Foerster LLP(57) **CLAIM**

We claim the ornamental design for a faucet dial, as shown and described.

DESCRIPTION

FIG. 1 is a front perspective view of a faucet dial showing our new design;

FIG. 2 is a rear perspective view thereof;

FIG. 3 is a front perspective view thereof showing environment;

FIG. 4 is a rear perspective view thereof showing environment;

FIG. 5 is a front view of the faucet dial of FIG. 1;

FIG. 6 is a side view thereof;

FIG. 7 is a bottom view thereof;

FIG. 8 is a top view thereof; and,

FIG. 9 is a side view of the opposite side of FIG. 6.

The broken lines shown in the drawings illustrate portions of a faucet dial that form no part of the claimed design.
